United States Patent Office

Des. 231,503
Patented Apr. 30, 1974

231,503

HAT

Winifred S. Potter, 3038 Potomac,
Dallas, Tex. 75205

Filed Jan. 27, 1972, Ser. No. 221,489

Term of patent 14 years

Int. Cl. D2—03

U.S. Cl. D2—256

FIG. 1

FIG. 2

FIG. 3

FIG. 1 is a plan view of a hat showing my new design, the material indicated being continuous throughout;

FIG. 2 is an end view thereof looking in the direction of line 2—2 on FIG. 1; and

FIG. 3 is a side elevational view thereof in wearing position showing the side opposite that shown in FIG. 1 with the front edge of the hat turned up.

I claim:

The ornamental design for a hat, substantially as shown and described.
